E. L. WILKISSON.

AUDIBLE ALARM FOR COOLERS FOR INTERNAL COMBUSTION MOTORS.

FILED OCT. 6, 1921.

Fig. 2.

Fig. 3.

Inventor:

Edward L. Wilkisson,

By his Attorney, Les. F. Math

UNITED STATES PATENT OFFICE.

EDWARD L. WILKISSON, OF BROOKLYN, NEW YORK, ASSIGNOR OF ONE-HALF TO
EMIL E. STEINIGER, OF LONG ISLAND CITY, NEW YORK.

AUDIBLE ALARM FOR COOLERS FOR INTERNAL-COMBUSTION MOTORS.

Application filed October 6, 1921. Serial No. 505,861.

To all whom it may concern:

Be it known that I, EDWARD L. WILKISSON, a citizen of the United States, and a resident of the borough of Brooklyn, county

5 of Kings, city and State of New York, have invented certain new and useful Improvements in Audible Alarms for Coolers for Internal-Combustion Motors, of which the following is a specification.

10 While applicable to the cooling systems of internal combustion engines generally, my improvements are designed more especially for use in conjunction with radiators, so called, with which automobile motors are 15 equipped for the purpose of reducing the temperature incidental to operation by means of a circulatory water vehicle in a manner well known in the art,—my object being to afford a sure and effective alarm 20 device which will audibly and automatically announce an increase in temperature of the cooling liquid vehicles sufficient to generate steam pressure within said radiator; and my invention consisting essentially 25 in combining with a radiator, a steam-actuated whistle positioned above the water level therein, substantially as and for the purpose herein set forth.

In the accompanying drawings I have 30 shown a practical embodiment of my invention in which my audible alarm is positioned on the screw cap usually provided for the closure of the filling neck of an automobile radiator, although the steam-announcing device may be otherwise positioned to communicate with the interior of the radiator above the normal water level thereof with like result, and without deviating from the spirit and intent of my invention in this 35 respect, which contemplates broadly any combination and arrangement of whistle and radiator adapted to utilize steam pressure in the latter as a sounding medium in a manner equivalent to that shown and described herein.

With this understanding,

Fig. 1, is a sectional elevation of the upper portion of a radiator, its filling neck, and closure cap, the latter having my audible 50 alarm mounted thereon;

Fig. 2, is a horizontal section taken upon plane of line 2—2, Fig. 1, and looking in the

direction of the arrows at the extremities of said plane line;

Fig. 3, is an elevation of the cap, etc., 55 shown in the preceding figures.

In Fig. 1 of the drawings, R, represents the upper medial portion of the tank of a radiator of an automobile, for instance, formed with the usual cylindrical filling neck N, and provided with the usual overflow pipe O.

The closure cap C, may be of any desired external configuration, and it is formed with a central opening c, for the accommodation of the whistle tube W, the lower portion of which is screw-threaded for engagement with a nut member w, for securing said whistle tube W, in position, the latter being formed with the annular bearing 70 shoulder w', acting in conjunction with said washer member w, and packings p, p, being interposed between the cap plate and the said parts w, w', to insure a tight joint.

The upper portion of the whistle tube W, 75 is also screw threaded for engagement with the dome section w², of the whistle, considered as a unitary device,—the lower portion of said dome section w², being of inverted cup shape, with relatively thin side walls, 80 the edges of which act as impingement surfaces for the steam ejected through the openings w³, w³, in the sides of the whistle tube w.

The lower portion of the nut member w, is 85 preferably flared outward, or of inverted funnel shape, to concentrate the flow of steam to and through the whistle tube W; and it will be noted that the dome member w², is adjustably mounted (by means of the 90 screw-threaded connection) on the whistle tube W, so that the tone or pitch of the whistle may be regulated according to desire or requirements.

The type of whistle herein shown is obviously only one of several of well known forms thereof that may be substituted and used for the purpose, with like result, so that I do not wish to limit myself in this respect, the pre-requisite being a sounding 100 device operable by steam pressure whenever generated within the radiator casing.

The temperature of the water used as a circulatory vehicle for the elimination of

excess of heat in the motor may reach as high as 170° to 180° Fahrenheit with efficiency, so that the boiling point of water (212°) is proximated. Hence, defective 5 pump action, or impediment of circulation from any cause, or excess of heat from carbonization, or retarded sparking and consequent slow combustion in the motor or other cause, soon results in the generation of 10 steam within the radiator casing, and overheating, with possible injury to both radiator and motor, so that positive and timely warning of such danger is most desirable in order that the same may be promptly 15 averted.

I am aware that the state of the art discloses means for visually indicating the presence of steam in an autoradiator, but my alarm is primarily and essentially an audible one, the presence of steam being indicated by sound in such manner as to be ef-

fective, where a purely visual sign might fail to draw attention to the danger involved.

Hence, while I do not seek to cover the 25 utilization of steam pressure within the radiator as a means of warning in the abstract, what I do claim, and seek to cover by Letters Patent, is,

The combination with a radiator, of a 30 closure cap therefor, a whistle tube extended through said cap and having openings and a threaded upper end, a chambered dome section on said threaded end in close proximity to the openings in said tube, the end 35 of said tube within the neck of the radiator being threaded, and a combined nut member and inverted funnel on said lower end.

EDWARD L. WILKISSON.
